UNITED STATES PATENT OFFICE

2,664,916

HYDRAULIC ELEVATOR DESCENT
CONTROL VALVE

Alvin M. Conley, Los Angeles, Calif.

Application August 20, 1951, Serial No. 242,689

6 Claims. (Cl. 137—653)

1

My invention relates to hydraulic elevator descent control valves, that is, to solenoid control valves designed to regulate the downtravel of hydraulic elevators.

Included in the objects of my invention are:

First, to provide a control valve of this class wherein the rate at which the valve opens and closes may be readily adjusted and whereby when the valve is incorporated in a hydraulic elevator control system, the starting and stopping periods during descent of the elevator may be so adjusted as to avoid undue acceleration or deceleration, yet permitting an adequate top speed of descent.

Second, to provide an elevator descent control valve wherein a relatively small, simple solenoid armature controls a bypass port to effect opening and closing of the main flow line.

Third, to provide an elevator descent control valve which is not appreciably affected by the change in load carried by the elevator.

Fourth, to provide an elevator descent control valve which lends itself to control systems wherein a large and a small capacity control valve may be connected in parallel to permit "inching" of an elevator to floor level.

Fifth, to provide a control valve of this type wherein in an emergency or during service of the elevator equipment, the valve may be manually operated, irrespective of the solenoid control element so as to permit controlled descent of the elevator, if desired, this being accomplished without disturbing adjustment of the valve.

Sixth, to provide a valve of this class wherein the maximum open position of the valve may be readily adjusted to control the top speed or descent without altering the "starting" or "stopping" characteristics of the valve and eliminating entirely a separate valve for the purpose.

With the above and other objects in view as may appear hereinafter, reference is directed to the accompanying drawing in which:

Figure 1 is a longitudinal sectional view of my hydraulic elevator descent control valve taken through 1—1 of Figure 2 and showing the solenoid unit in place.

Figure 2 is a sectional view thereof through 2—2 of Figure 1 with the solenoid unit omitted.

Figure 3 is a fragmentary sectional view through 3—3 of Figure 1 showing the throttle valve for controlling the opening and closing characteristics of the valve.

Figure 4 is a diagrammatical view illustrating the manner in which my valve may be incorporated in an elevator control system.

My control valve includes a valve body 1. The

2

valve body is provided with a lateral opening which receives an outlet fitting 2 having an outlet port 3 therein. Formed at the valve body in coaxial relation with the outlet port is a valve cylinder 4. A chamber 5 partially surrounds the valve cylinder and includes a portion interposed between the outlet port 3 and the cylinder 4. The chamber 5 communicates with an inlet port 6 which, in a construction shown, extends downwardly, but may, for convenience, be otherwise located.

The outlet port 3 is provided with a valve seat 7 facing toward the valve cylinder 4. The area of the valve seat 7 is smaller than the area of the valve cylinder. The valve cylinder receives a valve plunger 8 and a sealed ring 9 for sliding fit in the valve cylinder. The valve plunger is provided with a valve seat 10 which engages the valve seat 7. The valve seat 10 may be held in place by a pintle sleeve 11 which fits slideably in the outlet port 3. The pintle sleeve is notched in such a manner as to form, with the outlet, orifices which gradually increase in effective area as the valve is open.

A spring 12 extends between the plunger 8 and the inner end of the cylinder 4. The spring is preferably just sufficient to overcome the friction of the valve plunger and hold the valve seats 7 and 10 in mutual engagement. The wall of the valve body 11 at the inner end of the valve cylinder 4 is provided with an externally accessible stop screw 13 which may be adjusted to regulate the maximum open position of the valve plunger. The stop screw may be provided with a seal ring 14.

The upper end of the valve body is provided with a screw threaded cavity 15 which receives sealed guide socket member 16. A solenoid 17 surrounds the guide member and an armature 18 is slidably mounted in the guide member. The armature is provided with a depending valve tip 19. The valve tip 19 of the armature engages valve seat member 20 provided at the bottom of the cavity 15.

A passage 21 communicates between the underside of the valve seat member 20 and the outlet port 3, beyond the pintle sleeve 11, the passage extending from the valve body 1 into the outlet fitting 2 and intersecting a radial passage 22 therein. A bypass 23 extends between the radial passage 22 and the cavity 15 above the valve seat member 20. The radial passage 22 is provided between passages 21 and 23 with a valve seat controlled by an externally accessible, manually operated needle valve 24. As shown in Fig-

ure 3, the cavity 15 communicates by a bypass passage 25 with the chamber 5 and, therefore, with the inlet port 6. This passage is preferably provided with a constriction 26. The cavity 15 also communicates with the valve cylinder 4 through a bleeder passage 27. The bleeder passage 27 is intersected by a bore which receives a cylindrical throttle valve 28 having a transverse port 29.

My hydraulic elevator descent control valve is adapted to be installed in an elevator system such as shown diagrammatically in Figure 4. In such a system, a pump P delivers liquid, either water or oil, from a surge tank T to an elevator ram R to effect ascent of an elevator. If the pump be a positive displacement type, a momentary acting bypass valve V is provided to ease starting loads. This valve is the subject of a separate invention.

Two of my descent control valves may be employed. A main valve A of a relatively large capacity is connected across the pump P with its inlet communicating with the ram R and its outlet side communicating with the surge tank T. A secondary valve B of smaller capacity is similarly connected between the ram and the surge tank. Except for their capacities, valves A and B are identical in their construction. They may be electrically connected by means (not shown) to the elevator control system so that the main valve A or both valves may operate as the elevator approaches a floor. Then as the elevator moves closer to floor level, the main valve may close so that the auxiliary valve may "inch" the elevator into position.

Either valve operates as follows: When the solenoid is deenergized, the passageway, comprising the passages 21 and 25, between the inlet and outlet sides of the valve, is closed. The bleeder passage or branch passage 27 is in communication with the inlet port. Consequently, the valve cylinder 4 is subjected to the high pressure fluid existing at the inlet side of the valve body. Inasmuch as the area of the valve cylinder is greater than the differential area between the outlet port and the valve cylinder, the valve plunger is held in its closed position.

When the solenoid unit is operated, the fluid may bleed from the valve cylinder 4 to the outlet side of the valve, reducing the pressure in the valve cylinder so that the pressure existing in the inlet side of the valve may be applied to the differential area between the outlet port and the valve cylinder to urge the valve toward its open position. It will be noted that the constriction 26 insures the necessary pressure drop even though flow occurs through the bypass from the inlet to the outlet side of the valve.

The rate at which the valve opens is dependent upon the setting of the throttle valve 28. When the solenoid is again deenergized to close the bypass, the pressure existing in the inlet side of the valve is applied to the valve plunger forcing it to its closed position. The rate at which the valve closes is also dependent upon the setting of the throttle valve 28.

It can thus be seen that by adjusting the position of the throttle valve 28, the opening and closing cycle of the control valve may be regulated. Consequently, the acceleration or deceleration of the elevator is adjusted.

By adjustment of the stop screw 13, the maximum open position of the valve may be regulated. This adjustment determines the maximum descent speed of the elevator.

It is desirable, particularly during service of an elevator system or in the event of power failure, to be able to operate the control valve manually. This is accomplished by the needle valve 24 which, when opened, enables the descent control valve to be manually operated. Normally, the needle valve 24 is in its closed position.

Having fully described my invention, it is to be understood that I do not wish to be limited to the details herein set forth, but my invention is of the full scope of the appended claims.

I claim:

1. A valve for controlling the descent of hydraulic elevators, comprising: a valve body defining an outlet, a valve cylinder in alignment with said outlet, an inlet communicating between said valve cylinder and said outlet, a bypass communicating between said inlet and outlet and having a branch communicating with said valve cylinder; remotely actuated valve means controlling said bypass to bleed fluid simultaneously from said inlet and said valve cylinder; a throttle valve in said valve cylinder branch of said bypass to regulate flow of fluid into and out of said valve cylinder, and a valve plunger slideable in said valve cylinder and adapted to close said outlet.

2. A valve for controlling the descent of hydraulic elevators, comprising: a valve body defining an outlet, a valve cylinder in alignment with said outlet, an inlet communicating between said valve cylinder and said outlet, a bypass communicating between said inlet and outlet and having a branch communicating with said valve cylinder; a valve seat at said outlet confronting said valve cylinder and of lesser area than said valve cylinder; a valve plunger slideable in said valve cylinder and having a face engageable with said valve seat; remotely controlled valve means in said bypass to permit bleeding of fluid from said valve cylinder; and a throttle valve to regulate flow to and from said valve cylinder thereby to predetermine the rate of movement of said valve plunger during both the opening and closing cycles.

3. A valve for controlling the descent of hydraulic elevators, comprising: a valve body defining an outlet, a valve cylinder in alignment with said outlet, an inlet communicating between said valve cylinder and said outlet, a bypass communicating between said inlet and outlet and having a branch communicating with said valve cylinder; a valve seat at said outlet confronting said valve cylinder and of lesser area than said valve cylinder; a valve plunger slideable in said valve cylinder and having a face engageable with said valve seat; a solenoid actuated valve means in said bypass to permit bleeding of fluid from said valve cylinder; a throttle valve to regulate flow to and from said valve cylinder thereby to predetermine the rate of movement of said valve plunger; and a manual valve in parallel with said solenoid actuated valve to permit manual control of said valve.

4. A valve for controlling the descent of hydraulic elevators, comprising: a valve body defining an outlet, a valve cylinder in alignment with said outlet, an inlet communicating between said valve cylinder and said outlet, a bypass communicating between said inlet and outlet and having a branch communicating with said valve cylinder; a valve seat at said outlet confronting said valve cylinder and of lesser area than said valve cylinder; a valve plunger slideable in said valve cylinder and having a face engageable with

said valve seat; remotely controlled valve means in said bypass to permit bleeding of fluid from said valve cylinder; a throttle valve to regulate flow to and from said valve cylinder thereby to predetermine the rate of movement of said valve plunger; and an externally accessible adjustable stop for adjusting the travel of said valve plunger.

5. A control valve, involving: a valve body structure defining a right angularly related inlet and outlet, a valve cylinder coaxial with said outlet, the area of said outlet being less than the area of said cylinder, a chamber between said outlet and valve cylinder communicating with said inlet; said body structure also defining a bypass between said inlet and outlet including a branch communicating with said valve cylinder; remotely controlled valve means for said bypass to divert fluid into or bleed fluid from said valve cylinder; a throttle valve to regulate the rate of flow into and out of said valve cylinder; a valve plunger slideable in said valve cylinder and arranged to close said outlet; and an adjustable stop means protruding from said valve cylinder for regulating the maximum open position of said valve plunger.

6. A control valve, involving: a valve body structure defining a right angularly related inlet and outlet, a valve cylinder coaxial with said outlet, the area of said outlet being less than the area of said cylinder, a chamber between said outlet and valve cylinder communicating with said inlet; said body structure also defining

a bypass between said inlet and outlet including a branch communicating with said valve cylinder; a solenoid actuated valve means for said bypass to divert fluid into or bleed from said valve cylinder; a throttle valve to regulate the rate of flow into and out of said valve cylinder; a valve plunger slideable in said valve cylinder and arranged to close said outlet; an adjustable stop means protruding from said valve cylinder for regulating the maximum open position of said valve plunger, and a manually operated valve in parallel with said solenoid valve for manually controlling operation of said valve cylinder, irrespective of said remotely controlled valve means.
